(57) **CLAIM**

The ornamental design for an automotive wheel, as shown and described.

DESCRIPTION

FIG. 1 is a perspective view of an automotive wheel, showing our new design;

FIG. 2 is an enlarged front view thereof;

FIG. 3 is a perspective view of a second embodiment of an automotive wheel; and,

FIG. 4 is an enlarged front view thereof.

The broken lines are for illustrative purposes only and form no part of the claimed design.
